UNITED STATES PATENT OFFICE.

EDWARD F. WESTON, OF NEWARK, NEW JERSEY, ASSIGNOR TO WESTON ELECTRICAL INSTRUMENT CORPORATION, OF NEWARK, NEW JERSEY, A CORPORATION OF NEW JERSEY.

DOUBLE-RANGE VOLTMETER.

Application filed August 26, 1925. Serial No. 52,658.

This invention relates to a double range voltmeter for indicating voltages of either a higher or a lower range of values. The invention resides in an attachment adapted to be connected to the back of voltmeters of known type, such attachment containing a high range resistor and switching means for making the necessary connections to enable the voltmeter to indicate higher or lower ranges of voltages.

In the drawings:

Fig. 1 is a side elevation with parts shown in vertical section on a diametrical plane; Fig. 2 is a bottom view partly in section 15 on the horizontal plane indicated by line 2-2 of Fig. 4.

Fig. 3 is a front elevation of the attachment to the right of plane 3-3 of Fig. 1;

Fig. 4 is a rear view;

Fig. 5 is a diagram of the circuit connections.

Referring to Figs. 1 and 2, G represents a voltmeter of the known movable coil type, the coil K (see Fig. 5) being in circuit with a low range resistor C mounted inside the case. 1 and 2 are the main negative and positive terminals, in this instance serving also as a means for securing the attachment to the base of the voltmeter.

30 The attachment comprises a disk-shaped member L, preferably of the same diameter as the base of the voltmeter, having secured within it a high range resistor coil M.

The negative terminal 1 of the instrument 35 projects through the member L and serves as one terminal of the complete assembly, while the positive terminal 2 of the voltmeter does not extend beyond the member L but is adapted to be electrically connected to the low range binding post 3 or the high range binding post 4 which are carried by the member L. A conductor 5 connects the binding post 3 with a switch contact A which extends through the back of the attachment and which is normally engaged by the free end of a spring contact arm 6, the other end of the arm 6 being attached to the positive terminal 2 of the voltmeter. The binding post 4 is connected through the high 50 range resistor coil M to a post 20 carrying a spring arm 7 having a contact B thereon. The outer face of the member L is recessed as at 21 to receive the fixed end of the contact arm 7, the end of the arm engaging the sides of the recess 21 with a compara-

tively close fit, whereby the arm 7 is held in position to place the contact B in horizontal alignment with the low range contact A. The switch arm 6 is similarly confined against relative rotary motion by the walls 60 of the recess 22 in which the fixed end of the arm is held by the terminal post 2.

The switch arm 6 may be moved from its normal position in engagement with the contact A and into engagement with the contact B by means of an operating rod 8 which has a reduced end 8' extending through an aperture in the flange of the instrument housing and which at its opposite end carries a shouldered insulating bushing 70 9, the reduced outer end of which extends through an aperture in the free end of the switch arm 6.

While not limited in its application thereto, an instrument of this type is particularly useful in connection with radio receivers and a typical diagram of circuit connections is illustrated in Figure 5. As illustrated the switch arm 6 which is arranged to lie normally in contact with A 80 serves to connect the movable coil K and the low range resistor C in circuit across the A-battery.

If a higher range voltage, such as that of a B battery is to be measured, the arm 85 8 is pressed to bring arm 6 into engagement with contact B, when the circuit is made through the movable coil and both high and low resistor coils, thus enabling the higher range voltage to be indicated by the voltmeter.

It will be noted that the switch operating rod 8 is not positively connected to the instrument housing or to the switch arm, but is held in position between the instrument 95 flange and the switch arm 6 when the attachment base L is connected to the instrument housing by the instrument terminals 1 and 2. The positioning of the spring arms 6 and 7 by locating the ends thereof in recesses formed in the member L simplifies the construction since but one post or attaching member is employed for each spring arm. The construction is also simplified and the danger of an accidental short-circuiting of parts of the switch mechanism is reduced by the location of the lead 5 at the inner side of the disk member L.

It will be understood that the invention is not limited to the exact details of con-

struction herein shown and described since various changes in the parts, their relative size, shape and location may be made without departing from the spirit of my invention as stated in the following claims.

I claim:

1. An attachment to be connected to the base of a voltmeter for permitting the indication of voltages of different orders of magnitude, comprising a disk member having apertures through which the terminal posts of the voltmeter are adapted to be passed, a low range and a high range binding post carried by said member, a contact connected to said low range binding post, a high range resistor coil carried by said member and having one end thereof connected to said high range binding post, a second contact having one end thereof connected to said high range coil and having its outer end in alignment with said first contact, a spring switch arm having one end fixed to said member and having the free end thereof positioned between said contacts, and an operating rod having reduced portions at each end thereof, said reduced portions adapted to be positioned within apertures in the voltmeter flange and in the end of said switch arm, respectively.
2. The combination with a single range voltmeter, of an attachment mounted at the rear thereof and carrying a high range resistor coil, switch mechanism for alternatively placing said coil in or out of circuit with said instrument, and a longitudinally movable rod for operating said switch mechanism, said rod extending through the instrument flange and the switch arm, and having shoulders for confining said rod between said flange and said switch arm.
3. An attachment for converting a single range voltmeter into a double range instrument, said attachment comprising a member of insulating material having apertures therethrough for receiving the voltmeter terminals, a high and a low range binding post carried by said member, a multiplier coil on said member, a pair of switch contacts in longitudinal alignment, one of said contacts being connected to said low range binding post and the other contact being connected to said high range binding post through said multiplier coil, a spring switch arm having an end adapted to contact with a terminal of the voltmeter when the attachment is secured thereon and having a

free end lying between said contacts, and a longitudinally movable operating rod for said switch arm, said rod having a reduced end portion adapted to be supported by the casing of the voltmeter to which the attachment is fixed.

4. An attachment for converting a single range voltmeter to a double range instrument, said attachment comprising a disk member having apertures therethrough for receiving the voltmeter terminals, a multiplier coil, a pair of binding posts and switch mechanism for alternatively establishing the indicating circuit through one or the other of said binding posts, said switch mechanism including a spring switch arm and a spring contact arm having the free ends thereof in longitudinal alignment and having the fixed ends thereof positioned in and snugly engaging the sides of recesses found in the member.

5. An attachment for use with a single range voltmeter, comprising a disk member, a multiplier coil thereon, a pair of binding posts and switch mechanism for establishing the indicating circuit through either of said binding posts, said switch mechanism including a contact extending through said member, a connection at the inner face of said member and connecting said contact to one of said binding posts, a spring switch arm and a spring contact arm at the outer face of said member and having portions thereof in longitudinal alignment with said first contact.

6. An attachment for connection to the base of a voltmeter having a housing provided with a flange at the forward face thereof, said attachment comprising a disk member of the same diameter as the body of said voltmeter, a multiplier coil on said member, a plurality of binding posts, switch mechanism on said member and including a spring switch arm having an apertured end extending beyond said member and in longitudinal alignment with the flange of an instrument to which said attachment is fixed, and a switch operating rod having a reduced portion positioned in the aperture of said switch arm and having a reduced portion at the opposite end thereof adapted to pass through an aperture in the instrument flange.

In testimony whereof I affix my signature.

EDWARD F. WESTON.
